UNITED STATES PATENT OFFICE.

JAMES MILTON WILLIAMS, OF RENICK, MISSOURI.

FIFTH-WHEEL.

SPECIFICATION forming part of Letters Patent No. 398,869, dated March 5, 1889.

Application filed April 12, 1888. Serial No. 270,435. (No model.)

To all whom it may concern:

Be it known that I, JAMES MILTON WILLIAMS, a citizen of the United States, residing at Renick, in the county of Randolph and 5 State of Missouri, have invented certain new and useful Improvements in Fifth-Wheels; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 Figure 1 is a top view; Fig. 2, a section on line $x-x$; Fig. 3, a front view, and Fig. 4 a side view.

This invention relates to fifth-wheels; and it consists in the construction hereinafter set 20 forth.

In the annexed drawings, the letter A indicates the front axle, on top of which is secured the bottom plate, B, of the fifth-wheel. This plate has at its ends the recesses $b-b$, in which 25 are held the clips C C, which help to hold the plate to the axle, the projections $b'-b'$ preventing endwise slip. At its middle and on the front side of the plate B has the boss D, with the bore d. On each side of the boss the plate 30 B is made with a transverse enlargement or bar, E, having the perforated ears e, this bar being to receive the ends of the bolts F. Near its ends the plate B has underneath the pairs 35 of wings b^3-b^3 , which clasp the axle, and on top the two portions G G of the fifth-wheel circle. These portions have their ends $g-g$ beveled downwardly on top, as shown at $g'-g'$. Underneath the axle is the tie-plate H, through 40 the ends of which the bolts F F pass. To the bottom of the head-block I is secured the upper portion, K, of the fifth-wheel circle. This is semicircular, as shown in Fig. 1, has the upturned bevels $k-k$ on its ends $k'-k'$, and the diametric bar k^3 secured to the under side 45 of the head-block. This upper portion has the recesses $l-l$ to receive the head-block and

the enlargements $l'-l'$ for the tie-bolts L L, which pass above the head-block and are clipped by the plate l^2 above the spring l^3 . The upper portion is socketed at m into the 50 lower portion, the king-bolt M passing down through them and through the lower brace, n. From the middle of the bar k^2 a plate, N, passes to the circular part of the upper portion and beyond, as at n'. The prolongation n' 55 is channeled on top at n^2 . The perch O is secured at its front end, o, in the head-block by the bolt o', which passes down from the top brace, P. The bolts p p secure the perch, the rear end of the top brace and bottom brace, 60 and the prolongation n' together. On the bottom of the perch, which is of wood, is a metallic bar, q, the front end of which rests in the channel n^2 and against a shoulder, n^3 .

This makes a very strong and rigid device. 65 By having the ends of the circles curved if the vehicle should be turned too far and the wheels pass the beveled ends would cause them to ride past each other when the vehicle was straightened. By having the two parts 70 G G there is sufficient bearing below with due strength and lightness. The top circle, K, being curved around, furnishes all the necessary bearing-surface as the wheel turns.

What I claim is—

1. The combination of the plate B, having the pairs of wings b^3-b^3 , the enlargements E E, and the recesses $b-b$, with the clips C C, the bolts F F, the axle A, and the tie-plate H, as set forth.

2. The combination of the perch O, the head-block I, the two portions of the fifth-wheel socketed together, the king-bolt M, the braces P and n, the plate N, having the prolongation n', and the bolts p and o', as set forth.

In testimony whereof I affix my signature in presence of two witnesses.

JAMES MILTON WILLIAMS.
